F. C. ECKELMAN

LOCK CONTROLLED CUT-OFF

Filed July 23, 1923

Frederick C. Eckelman
INVENTOR.

BY Victor J. Evans,

ATTORNEY.

WITNESS:

J. B. White

UNITED STATES PATENT OFFICE.

FREDERICK C. ECKELMAN, OF NEW YORK, N. Y.

LOCK-CONTROLLED CUT-OFF.

Application filed July 23, 1923. Serial No. 653,334.

To all whom it may concern:

Be it known that I, FREDERICK C. ECKELMAN, a citizen of United States, residing at New York city, in the county of New York and State of New York, have invented new and useful Improvements in Lock-Controlled Cut-Offs, of which the following is a specification.

This invention relates to lock controlled 10 cutoffs.

More particularly the invention relates to lock controlled cutoffs to be employed in conjunction with a conduit between a source of fuel supply and a point of consumption 15 of the fuel.

Some of the objects of the present invention are: To produce a lock controlled cutoff for a connection in a conduit which includes a cutoff means for establishing and 20 disestablishing the passage through said conduit and operating means for operating the cutoff means, the operating means being operable by virtue of the operation of the locking means employed, and safety locking means operative to maintain the cutoff means in a condition to disestablish the passage through said conduit to prevent the 25 operation of the cutoff means when the operating means is destroyed; to employ cutoff means in the fuel supply conduit which is under the influence of separate and distinct locking means, one locking means being operable for the successful operation of the cutoff means, and the other locking means 30 being operable automatically upon the destruction of a part of the means for effecting the operation of the cutoff means.

With these and other objects in view, the 40 invention resides in the particular provision, combination, relative disposition and operation of parts hereinafter fully described and illustrated in the accompanying drawing, in which:—

Figure 1 is a sectional elevation.

Figure 2 is a sectional view taken on the line 2—2 of Figure 1.

Figure 3 is a sectional view taken on the line 3—3 of Figure 1.

Figure 4 is a sectional view taken on the 50 line 4—4 of Figure 1.

Figure 5 is a sectional view taken on the line 5—5 of Figure 1.

Figure 6 is a perspective view of a part 55 of the cutoff operating means.

Figure 7 is a perspective view of the operating means.

The lock controlled cutoff of the present invention has some of the features of the device disclosed in a patent granted to me #1,214,441. The specific features of construction of those parts in this device which are used in the device of the patent mentioned may be fully understood as to construction and operation by the description and illustration of the said patent. 60 65

The device of the present invention, generally, comprises a conduit 10, cutoff means 11 connected to said conduit for establishing and disestablishing the passage therethrough, cutoff operating means 12, permutation locking means 13, which controls the operation of the cutoff operating means, and safety locking means 14 which operates in conjunction with the means 12 to prevent the 70 operation of the cutoff means 11 in the event that portions of the means 12 are cut, broken or otherwise destroyed. 75

The conduit 10 in the present instance is intended to be connected between a source of fuel supply such as gasoline, and the manifold of an engine of an automobile. As 80 stated the cutoff means 11 is arranged in operative connection with the conduit 10 for establishing and disestablishing communication between the fuel supply and said manifold. The said cut-off means 11 comprises a casing 16 made of plates 17, 18 and 19 and parts 20 and 21 between which the part 16 is bolted by locking bolts 22. The plate 18 has an opening 23, opening 24, 85 opening 25 and opening 26. Because of the fact that the plate 18 is arranged between the plates 17 and 19 recesses will be defined by virtue of said openings. A cutoff 27 is pivoted as at 28, and is disposed for movement in the opening 23 to either close or open the aligned holes 29 in the plates 17 and 19 and the parts 20 and 21 which communicate with the passage of the conduit. 90 95

A portion of the cutoff 27 has teeth 30. 100

In order to effect the movement of the cutoff 27 the means 12 hereinbefore mentioned is employed. The means 12 comprises a rack 31 which is disposed in the opening 25, a spring 32, flexible connection 33, push button 34, member 35 and push button 36. The teeth of the rack 31 are in meshing engagement with the teeth 30; the spring 32 is arranged between the end of the rack 31 and the end wall of the opening 25; one end of the connection 33 is attached to the rack 31 and the opposite end thereof is con- 105 110

connected to a part 37. The part 37 is under the influence of a spring 38 surrounding the reduced part 39 of the button 34 and has a portion 40 extending in a bore in the part 39 and is held against separation but is allowed to have relative movement with respect to the part 39 by virtue of a pin and slot connection 41. The part 37 is bifurcated as at 42 for a purpose to appear. The 10 push buttons 34 and 36 and the member 35 are arranged in a casing 43. The member 35 is arranged for movement and is disposed between the push buttons 34 and 36. The said member 35 has a tongue 44 and oblique 15 kerf 45 and a nose 46. The member 35 has slidable movement and this is caused by virtue of a pin 47 disposed in the kerf 45; the said pin being carried by the furcations 48 of said button 36. The push button 36 20 is acted upon by a spring 49. When the holes 29 are obstructed by the cutoff 27, the push button 34 will be down or in and held in such position by virtue of the co-action of the nose 46 with the spring pressed 25 latch 50 carried by the button 34. At this time the spring pressed dog 51 has a portion thereof in engagement with a tooth 52 on a portion of the cut-off 27; the said dog has a tail 53 which co-operates with a tooth 30 54 on a portion of the cutoff 27. The dog 51 and teeth 52 and 54 constitute an escape- 35 ment means. A flexible connection 55 is connected to the dog 51 and to one end of a spring pressed part 57 arranged in the cas- 40 ing 43 in alignment with the part 37. It should now be manifest that if the push but- 45 ton 34 is allowed to move upwardly, the spring 58 of the part 57 will cause said part 57 to move upwardly with the result that the dog 51 will be put in a neutral position which action will be followed immediately 50 by the movement of the rack 31 due to the further movement of the push button 34 by virtue of the action of the spring 39 while the spring 38 serves to hold the feet of the part 37 seated against a stationary disk 38', and to take up lost motion between the push button 34, part 37 and part 57 positively and evenly thus causing the cutoff to move posi- 55 tively and evenly to a position in which the holes 29 will be unobstructed. The pressure of the spring 38 is greater than the spring 32 with the result that said spring 38 not only prevents lost motion between the parts mentioned but upon pressure of the button 34 the spring 38 also acts to keep the valve portion of the cut off 27 in closed position. Upon releasing the button 34 to an inoperative position the tension of the spring 38 60 is also released.

In order that the push button 36 may be pushed inwardly to effect the movement of the member 35 it is necessary to operate the locking means 13 which is substantially 65 similar in construction and operation of the

locking means disclosed in the aforesaid patent, whereupon the tongue 44 will be allowed to enter aligned recesses 59 in parts of the means 13. When the recesses 59 are aligned the member 35 may be reciprocated 70 by operating push button 36 either to permit the push button 34 to move outwardly or to permit the same to be pushed inwardly.

The flexible connections 33 and 35 are encased by a tubing 60 to prevent unauthorized manipulation with the parts of the device. To further protect against the trespassers, means 14 before mentioned is provided and consists of a flexible connection 61 connected to a ball 62 under the influence of a spring 63; the opposite end of the connection 61 being attached to a portion of the bushing 64; and the ball and spring disposed in the opening 26, one wall of which is inclined so that when connection 61 is 85 cut the ball will be forced into the small end of the opening 25 to move against the rack 31 to hold the latter against movement and the cutoff 27 in closing position. Extra 90 connections such as the ones 33, 55 and 61 95 may be employed to foil trespassers. The connections mentioned are preferably of piano spring steel wire. The tubing 60 extends from within the portion of the casing 16 to within a portion of the bushing 64 which latter is held in place in a portion of the casing 43 by screws or the like.

From the foregoing it will be manifest that by manipulating permutation means in a proper manner the recesses 59 may be brought into alignment whereupon the push button 36 may be pushed inwardly and the push button 34 and connected parts will be operated automatically to allow the cutoff to move automatically to an open position; the push button 36 moving to a normal position when pressure thereon is released; that by pressing inwardly on the button 34 the cut-off 27 may be moved to a closing position and in the event that either of the 110 connections 55 and 61 are cut or broken it will be impossible to move the cutoff 27 out of its closing position.

What is claimed as new is:—

1. A lock cut-off for connection in a conduit to establish and disestablish the passage therethrough comprising locking means, cut-off means whose operation is governed by the operation of said locking means, and cut-off operating means operable by virtue of the operation of said locking means, said cut-off operating means including a push button, a spring pressed latch laterally projecting from said push button, slotted means included in said locking means for receiving the latch to prevent movement of the push button, a second push button, a pin thereon and being movable in the slot to reciprocate said slotted means into or out of engagement with said latch, a spring 115 120 125 130

actuated rack, teeth on a portion of said cut-off means which mesh with the teeth of said rack and encased in guided connection between said push button and said rack.

5. 2. A lock cut-off for connection in a conduit to establish and disestablish the passage therethrough comprising locking means, cut-off means whose operation is governed by the operation of said locking means, cut-off operating means operable by virtue of the operation of said locking means, and safety locking means a spring pressed ball which co-operates with said cut-off operating means to prevent the operation of said 10 cut-off means upon the destruction of a part of said safety locking means.

3. In a device in which a cut-off operates to establish and to disestablish a fuel passage, lock controlled operating means for 20 effecting the operation of said cut-off to move the latter for establishing and disestablishing said fuel passage, said operating means including a push button, a spring pressed part movable in and connected to 25 said push button, a spring actuated rack whose teeth mesh with teeth of said cut-off

an encased flexible member between said rack and said spring pressed part, and a dog engageable with said cutoff and being movable upon movement of the cutoff actuating means.

4. A lock controlled cutoff for the conduit arranged between the intake manifold and the gasoline tank of a motor operated vehicle, said lock controlled cutoff comprising a 30 casing arranged in the conduit, a plate included in said casing and being provided with an elongated opening centrally disposed thereon and communicating at one end thereof with the bores of the conduit, the cutoff pivotally mounted in said casing for slidable movement in the elongated opening and controlling the bore, means for moving said cut-off including the lock, a 35 spring pressed ball movable in an opening having an inclined wall and formed in the plate, and said ball being adapted to contact the rack for a cammed action thereon as described.

In testimony whereof I have affixed my 40 signature.

FREDERICK C. ECKELMAN.
